C. HEINZEN

BEVERAGE SHAKER

Filed Dec. 21, 1923

Inventor:
Carl Heinzen,
By Fisher, Towle, Clapp & Doane
Atty's.

UNITED STATES PATENT OFFICE.

CARL HEINZEN, OF CHICAGO, ILLINOIS; HENRIETTE E. HEINZEN ADMINISTRATRIX
OF SAID CARL HEINZEN, DECEASED.

BEVERAGE SHAKER.

Application filed December 21, 1923. Serial No. 681,908.

My invention has reference more particularly to devices which are commonly known as cocktail shakers, and are designed for mixing and cooling beverages.

5 The principal objects of my invention are to provide a convenient device for mixing and cooling beverages, wherein the beverage is separated from the ice or other cooling medium so that the beverage is not diluted 10 or otherwise impaired or contaminated by direct contact therewith; to effectively seal both of the compartments; to render all the parts readily accessible for thorough cleaning; and in general, to provide a simple and 15 effective mixer or shaker of this character wherein the beverage may be readily mixed and cooled and poured out without coming in contact with the ice or other cooling medium.

20 On the drawings:

Fig. 1 is a vertical sectional view of a cocktail shaker embodying my improvements;

Fig. 2 a side view of the main portion 25 thereof;

Fig. 3 a side view of the cap; and

Fig. 4 a similar view of the cover of the cocktail shaker.

Referring to the drawings, the reference 30 numeral 1 indicates the main receptacle which is in the form of a truncated cone, and has a tubular shell or cylinder 2 therein, which is permanently secured to the bottom of the receptacle 1 by soldering as indicated 35 at 3, or in any other suitable manner, said cylinder being spaced from the wall of the receptacle 1 so as to form an annular chamber 4 between the receptacle 1 and the shell 2. The shell 2 projects upwardly above the 40 receptacle 1 as shown in Figs. 1 and 2 and preferably has the upper end tapered slightly as indicated at 5 so as to be snugly engaged by the correspondingly tapered neck 6 of the cover 7. At the lower edge the 45 cover 7 is formed with an annular flange 8 which is flared slightly so as to effect a wedging engagement with the tapered portion 9 at the upper end of the receptacle 1.

The arrangement of the neck 6 of the cover 50 and flange 8, and the taper of the interfitting parts is such that when the cover 7 is pressed in position, a tight fit is effected between the neck 6 of the cover 7 and the

tapered upper end 5 of the cylinder 2 and also between the flange 8 and the upper portion 55 9 of the receptacle 1.

A cap 10 having an annular wall tapered to fit snugly against the exterior of the neck 6 has a gasket 11 therein to engage the upper edge of the neck and also the upper edge of the tapered portion 5 of the cylinder 2, the latter being extended upwardly to a position substantially flush with the upper edge of the neck 6. This cap 10 therefore, when placed in position, not only seals the upper 60 end of the cylinder 2 but also serves at the same time by means of the gasket 11, to additionally seal the joint between the neck 6 of the cover 7 and the tapered upper end 5 of the cylinder 2.

In practice the chamber 4 contains the ice or other cooling medium and the cylinder 2 the beverage which is to be mixed and cooled, and it will be thus seen that the beverage is entirely separated from the ice 70 or other cooling medium. The ice is placed in the compartment 4 and the cover 7 placed in position so as to seal the connection between the upper edge of the receptacle 1 and the lower edge of the cover 7, and the 75 neck 6 at the same time seats against the upper end of the cylinder 2 so that the ice chamber is thoroughly closed. The beverage is then poured into the upper end of the cylinder 2 and the cap 10 applied, and by 80 shaking the device the beverage is thoroughly mixed and cooled.

After the beverage has been sufficiently mixed and cooled, the cap 10 is removed and the beverage poured from the cylinder 85 2, the ice and water in the chamber 4 being sealed therein by the fitting of the joints so that it does not discharge as the beverage is poured out.

It is noted that the tapered upper end 90 portion of the cylinder or inner liquid receptacle 2 and the tapered neck of the cover 7 project to a considerable extent above the main body of the cover and form in effect a suitable pouring spout for the liquid receptacle.

While I have shown and described my invention in a preferred form, I am aware that various changes and modifications may be made without departing from the principles of my invention, the scope of which is 100 105

to be determined by the appended claim.

I claim as my invention:

A beverage shaker comprising an outer ice receptacle having an upwardly tapering rim, an inner beverage receptacle rigidly fixed to the bottom of the ice receptacle, extending above the latter and having a tapering upper end portion spaced above the rim of the ice receptacle, a slip cover of inverted cup shape having a flaring rim snugly fit-

ting the outer surface of the tapering rim of the ice receptacle, and said cover having a tapering neck projecting from its upper end and snugly fitting the outer surface of the tapering upper end portion of the beverage receptacle and forming therewith a pouring spout for the beverage receptacle, and a closure cap for the latter fitting over said tapering neck, substantially as described.

CARL HEINZEN.
